CLAIM

The ornamental design for a tool handle for replaceable
knife blades, as shown.

DESCRIPTION

FIG. 1 is a bottom plan view of a tool handle for
replaceable knife blades showing my new design;

FIG. 2 is a left side elevational view thereof;

FIG. 3 is a top plan view thereof;

FIG. 4 is a right side elevational view thereof;

FIG. 5 is a front elevational view thereof; and,

FIG. 6 is a rear elevational view thereof.
